UNITED STATES PATENT OFFICE.

JOSEPH GUERRA, JAMES GUERRA, AND NICHOLAS MASONE, OF BROOKLYN, NEW YORK.

DESIGN FOR A RADIATOR ORNAMENT OR THE LIKE.

Application filed September 13, 1927. Serial No. 23,401. Term of patent 3½ years.

To all whom it may concern:

Be it known that we, JOSEPH GUERRA, a citizen of the United States, JAMES GUERRA, a subject of the King of Italy, and NICHOLAS MASONE, a citizen of the United States, residents of the city of New York, borough of Brooklyn, in the county of Kings and State of New York, have invented a new, original, and ornamental Design for Radiator Ornaments or the Like, of which the following is a specification, reference being had to the accompanying drawing, forming a part thereof.

The figure is a perspective view of a radiator ornament, showing our new design.

We claim:

The ornamental design for a radiator ornament or the like, as shown.

JOSEPH GUERRA.
JAMES GUERRA.
NICHOLAS MASONE.
